UNITED STATES PATENT OFFICE.

DANIEL D. WHITNEY, OF CORNWALL, NEW YORK, ASSIGNOR TO THE WHITNEY COUPLING COMPANY, OF WHITINSVILLE, MASSACHUSETTS.

STRAP-LOOP FOR CARRIAGES.

SPECIFICATION forming part of Letters Patent No. 445,105, dated January 20, 1891.

Application filed July 11, 1890. Serial No. 358,393. (No model.)

To all whom it may concern:

Be it known that I, DANIEL D. WHITNEY, of Cornwall, county of Orange, State of New York, have invented an Improvement in Safety Strap-Loops for Pole-Carriages, of which the following description, in connection with the accompanying drawings, is a specification, like letters on the drawings representing like parts.

- 10 In pole-carriages as now made the whiffletrees are fastened to a cross-bar on the pole by suitable pivotal connections, and said cross-bar is itself connected at each end to a suitable part of the gearing by safety-straps.
- 15 As a means for attaching the safety-straps to the cross-bar, loops are provided, which are secured to the under side of the cross-bars at one side of the pivotal connections of the whiffletrees.
- 20 This invention has for its object to construct an attaching device for such safety-straps by which the line of pull shall be in a direct line or under the pivotal connections of the whiffletrees, and to carry out this invention I have formed said loops directly on the under plate of the pivotal connections of said whiffletrees. Such construction I have found to be very much cheaper and more durable than any form known to me, and also
- 25 30 may be much more readily attached.

My invention consists in details of construction to be hereinafter pointed out.

Figure 1 shows in rear side view a portion of a whiffletree and cross-bar and pivotal connections thereof and a loop for the safety-strap; Fig. 2, a vertical section of the parts shown in Fig. 1, taken on the dotted line x ;

Fig. 3, a plan view of the under plate, showing the loop formed on it.

The whiffletree a and cross-bar b and pivotal connections thereof, are all of usual or suitable construction.

The pivotal connection, as herein represented, comprises contact-plates c c' , bolt c^2 , under plate c^3 , having a socket formed in it 45 to receive a yielding cushion c^5 , a washer c^6 , and nut c^7 .

To provide a loop for the safety-strap d , by which the ends of the cross-bar b are fastened to the gearing, and to so locate said loop that 50 the strap will pull in a direct line with the bolt c^2 , I have formed said loop on the under plate c^3 , as represented at d' . This loop d' may be formed cheaply in this way, and the plate c^3 , integral with which it is formed, will 55 have three screws or means for holding it in place on the under side of the cross-bar b' .

I claim—

The cross-bar, whiffletree, and whiffletree-connections, combined with the under plate 60 c^3 , having a socket formed therein on its under side, a yielding cushion in said socket, a retaining-nut, and a loop d' , integral with said under plate and extended from its upper part at right angles thereto, substantially as described.

In testimony whereof I have signed my name to this specification in the presence of two subscribing witnesses.

DANIEL D. WHITNEY.
